MULTIPLE COPY TYPEWRITING MACHINE

Lewis D. Nelson, Coldwater, Mich., assignor to
 James C. Trimby, Detroit, Mich., and Harry D.
 Atwood, Coldwater, Mich.

Application May 22, 1933, Serial No. 672,197

10 Claims. (Cl. 197—153)

This invention relates to the printing of a plurality of copies in a typewriting machine by one or more auxiliary inking ribbons lying alongside the main ribbon and disposed between successive sheets of papers in the machine.

The general objects of the invention is to provide a new and improved mechanism for the above purpose which is simple and inexpensive in construction, which is adaptable readily to standard typewriting machines, which is reliable in operation and will withstand the rough usage encountered in such machines, and which is convenient to operate.

Another object is to provide, in a typewriting machine, novel means for supporting a copy-printing ribbon for bodily movement into and out of printing position behind the main ribbon and for endwise advancing movement without at the same time interfering with the typist's vision of the work being printed by the main ribbon.

A further object is to provide a new and improved means for effecting automatic advance of a copy-printing ribbon mounted in the manner above described.

The invention also resides in the novel construction of the ribbon supporting and the ribbon advancing means which enables the position of the copy-printing ribbon to be adjusted readily and the ribbon to be removed and replaced conveniently.

Other objects and advantages of the invention will become apparent from the following detailed description taken in connection with the accompanying drawings, in which

Figure 1 is a fragmentary perspective view of a typewriting machine equipped with a copy-printing mechanism embodying the features of the present invention.

Fig. 2 is a fragmentary vertical cross-section of the machine shown in Fig. 1 with both of the copy-printing ribbons in printing position.

Fig. 3 is a section taken along the line 3—3 of Fig. 2.

Fig. 4 is a perspective view of one of the cranks of the ribbon advancing mechanism.

Fig. 5 is a fragmentary sectional view taken along the line 5—5 of Fig. 2.

Fig. 6 is a sectional view taken along the line 6—6 of Fig. 7.

Fig. 7 is a side elevational view of the mechanism shown in Fig. 1.

Fig. 8 is a section taken along the line 8—8 of Fig. 3.

Fig. 9 is a section taken along the line 9—9 of Fig. 8.

While the invention as disclosed in the drawings is embodied in an attachment for a standard typewriter, it will be apparent that the invention is not limited to such use but is applicable to any type of printing machine in which a plurality of copies are printed simultaneously. It is to be understood therefore that I aim to cover all modifications and alternative constructions falling within the spirit and scope of the invention as expressed in the appended claims.

Referring now to the exemplary embodiment shown in the drawings, the numerals 10 and 11 represent the front and side members of the carriage of a standard typewriter rotatably supporting a paper platen 12 opposite which the main ribbon 13 is led through guides 14. Step-by-step rotation of the platen to effect line-spacing and lateral shifting of the carriage are effected in the usual way by actuation of a horizontally swingable lever 15 which is pivoted at 16 and operates a pawl and ratchet mechanism to advance the platen.

In accordance with the present invention, additional copies are printed on sheets of paper disposed behind the main ribbon by one or more auxiliary ribbons 17 and 18 located between the proper paper sheets on the carriage. For example, if five copies are to be made, the second and fourth sheets of paper are transparent and the ribbons 17 and 18 disposed behind these sheets respectively. If only one copy is desired in addition to that printed by the ribbon 13, only the ribbon 17 would be used and its forward surface would be masked properly to avoid printing on the back of the first sheet.

To support the ribbon 17 in printing position as shown in Fig. 1 and for endwise movement longitudinally of the platen 12, the opposite ends of the ribbon are wound upon spools 19 and 20 and the intermediate portion extends through guide slots 21 in arms 22. The opposite ends of the ribbon 18 are similarly wound upon spools 23 and 24 and the intermediate portion extended between guide arms 25.

To support the ribbon 17 for independent bodily movement of its intermediate portions into and out of active or printing position, the spools 19 and 20 are rotatably mounted on the free ends of arms 26 which are pivotally mounted on the paper carriage to swing forwardly and downwardly and carry the ribbon into printing position alongside the platen and behind the main ribbon. The spools 23 and 24 are mounted in a similar manner upon the free ends of arms 27. The arms of each pair are rigidly connected for

movement in unison toward and away from the platen. To provide such a connection and locate the same so as not to obstruct the typist's vision of the matter being printed by the main ribbon, 5 the ends of the arms 27 opposite the spools 23 and 24 are rigidly secured to bushings 28 driven onto the end of a tube 29 adjacent the ends of the latter. The extreme ends of the bushings are journaled in bearings on the ends of brackets 30 10 projecting rearwardly from and detachably secured as by bolts 31 to plates 32 which are detachably clamped upon the side frames 11 of the carriage. The bearing brackets 30 may be shaped differently for different makes of type- 15 writing machines, the arrangement preferably being such as to locate the tube 29 immediately behind the usual paper rest 32a. The arms 26 are made rigid with bushings 33 which are pressed onto the ends of a tube 34 enclosing and 20 rotatably supported by the tube 29. By locating the bushings side by side and adjacent the bearing, the arms 26 and 27 are held effectually against lateral displacement. It will be observed that with the arms thus mounted, they may be 25 swung down into a position overlying the platen 12 or may be swung backwardly into an out-of-the-way position behind the paper rest 32a.

In the present instance, the spools are made in two separable parts to facilitate removal and re- 30 placement of the copy ribbons. Each comprises a hub (Fig. 3) in the form of a sleeve 33a having outer and inturned flanges 34 and 35 at one end. The other end of the sleeve is adapted to receive thereon in telescoping relation a sleeve 36 onto 35 which the ribbon is wound and held in place by a flange 37. The sleeve 36 is adapted to telescope snugly on the sleeve 33a, one end of the ribbon extending through a slot in the sleeve 36 and becoming firmly wedged between the two sleeves 40 as the latter are united to form the spool.

The spools 19 and 20 are loosely mounted on aligned short shafts 37 (Figs. 3 and 8) extending through and journaled in a bushing 38 carried by enlargements 39 on the forward ends of the 45 arms 26. The inner ends of the shafts project loosely through the opening defined by the spool flange 35 which is disposed between two disks 40 of friction material. A nut 41 disposed within the sleeve 33a and threading onto the inner end 50 of the shaft 37 is tightened sufficiently to compress a concave disk 42 of resilient metal between the adjacent disk 40 and a metal disk 43 whereby to develop the desired frictional resistance opposing rotation of the spool for a 55 purpose which will appear later.

The spools 23 and 24 are similarly supported by plates 44 depending from and detachably secured by pin and slot connections 45 to the free ends of the arms 27 on the inner sides thereof 60 whereby to locate the spools in the same vertical planes as the spools 19 and 20. The arms 26 are made shorter than the arms 27 so that the spools 23 and 24 are supported at the same level as but in front of the spools 19 and 20 when in 65 printing position. To provide for vertical adjustment of the ribbons, the guide arms 22 and 25 have adjustable pin and slot connections with the enlargements 39 and the plates 44. Horizontal adjustment of the ribbon 17 is obtained through the pin and slot connections 31 70 which may be loosened to enable the entire supporting tube assembly to be shifted horizontally along the plates 32. Horizontal adjustment of the ribbon 18 is permitted at the joints 45. By 75 virtue of the different provisions for adjustment

of the ribbon positions and for location of the tubes by which the ribbons are supported, the attachment may be applied readily to different standard makes of typewriters.

When the arms 26 are swung forwardly and 5 lowered to the position shown in Fig. 1, plates 46 secured to and spaced from the arms engage and rest upon ledges 47 (Figs. 1 and 9) on angularly shaped members 48 secured to the plates 32. Flanges 49 upstanding from the plates 32 provide 10 upwardly opening slots 50 into which headed pins 51 become seated as the arms 27 are lowered into printing position. The arms are thus supported in an accurately defined position and held against lateral displacement. Similar pins on the plates 15 44 enter similar notches as the arms 27 are swung down into place. In the lowermost position of the arms 27, projections 52 on the plates 44 engage and rest upon ledges 53 formed in the arms 26. 20

From Fig. 2, it will be seen that the ribbon 18 leaves the spools 23 and 24 on the rear side of the latter and extends substantially vertically to the guide bars 25. To avoid sharp turns in the ribbon 17 and a consequent increase in driving 25 friction, this ribbon leaves the spools 19 and 20 from the forward sides of the latter, that is, on the sides adjacent the spools 23 and 24. The ribbon 17 extends onto the guides 22 around rollers 54. The lower ends of each pair of guide arms 30 22 and 25 are maintained in spaced relation as by bending one of the arms laterally as indicated at 55 (Fig. 2). Any possibility of the ribbons being pinched between the two arms during advance 35 thereof is thus avoided.

The invention contemplates advancing the intermediate portion of each copy-printing ribbon automatically and in an endwise direction during normal operation of the typewriting machine while the ribbons are in printing position. In the 40 present embodiment, such advance is effected as an incident to operation of the line-spacing or carriage return mechanism through the medium of a link slide bar 56 mounted adjacent the arm 21 and guided at its forward end by the member 48 and a headed pin 48a anchored in the member 48 and projecting through a slot in the slide. The bar is thus adapted for horizontal endwise reciprocation transversely of the axes of the spools. Rigid with and projecting downwardly 50 from the forward end of the slide is an arm 57 having a notch 58 into which projects an arm 59 integral with the line-spacing slide 59a (Fig. 7) and actuated by an arm 15a on the lever 15. As the lever is swung toward the right, as viewed in 55 Fig. 1, the slide is shifted rearwardly, being returned to its normal forward position upon retraction of the lever by the usual return spring.

Reciprocation of the slide 56 imparts a unidirectional step-by-step advancing movement to 60 the spool 19 through the medium of a pawl and ratchet unit 60 mounted on the adjacent arm 26 and having a connection with the slide which is disengaged and engaged automatically upon raising and lowering the arms. Herein the unit 60 65 includes a crank member in the form of two disks 61 (Fig. 4) riveted together in spaced relation and loosely pivoted on the outer end of the shaft 37 between the arm 26 and the plate 46 carried thereby. A pin 62 carrying a flanged roller 63 at 70 its outer end projects from the upper or free end of the crank member through a horizontally extending slot 64 in the plate 46 which slot serves to define limit positions between which the crank 75 may swing. As the arms 26 are swung down-

wardly, the roller 63 enters an upwardly opening notch 65 in the slide 56. A spring 66 acting between the plate 46 and the outer disk 61 normally tends to oscillate the disks to the right hand end of the slot 64 (Fig. 7) thereby positioning the roller 63 for entry into the notch 65.

Fast on the shaft 37 between the disks 61 is a ratchet wheel 67 which is adapted to be advanced in a clockwise direction (Fig. 8) by pawls 68 pivotally mounted between the disks and urged by spring 69 into engagement with the ratchet teeth. The pawls have teeth 70 which are spaced along the periphery of the ratchet so that when one tooth is engaging one of the ratchet teeth to advance the ratchet, the other pawl tooth will be disposed between two of the ratchet teeth. This arrangement gives the effect of a substantially closer spacing of the teeth for the purpose of reducing the lost motion during each stroke of the pawls. The ratchet wheel is held against retraction and the development of slack in the ribbon is avoided by the provision of double check pawls 71 having similarly spaced teeth and pivoted on a pin 72 connecting the plate 46 and the adjacent arm 26.

Mounted on the arm 27 and associated with the spool 23 is a ratchet unit 73 which is of the same construction as the unit 60 but which is mounted in inverted relation with its flanged roller 74 disposed at the lower edge of the crank disks and adapted to enter an upwardly opening notch 75 in the slide 56. By virtue of this inverted relation of the oscillatory ratchet units 60 and 73, it will be apparent that these units will advance their ratchet wheels in opposite directions upon rearward movement of the slide 56. Accordingly, the spools 19 and 23 will be rotated in opposite directions and the vertically extending portions of the ribbon between the spools and the guide slots will move in the same direction because the ribbons leave the spools on adjacent sides thereof for the reasons above mentioned.

In order that the direction of feed of the copy-printing ribbons may be reversed, means is provided for applying the movement of the slide 56 to the pair of spools at either end of the platen. This means involves the provision of ratchet units 76 and 77 for the spools 20 and 24, a clutch for enabling each spool to be coupled positively to its supporting drive shaft 37, and means for transmitting the motion of the slide 56 to the other end of the platen for actuation of the ratchet units 76 and 77. To thus transmit the motion of the slide, a second similarly mounted slide 78 has notches 79 and 80 positioned to receive the flange rollers of these ratchet units. At their rear ends, the slides 56 and 78 are joined by a pin and slot connection 81 to the free ends of cranks 82 which are rigid with opposite ends of a shaft 83 projecting through and loosely supported by the tube 29.

Referring to Figs. 1, 2, and 3, each of the clutches above referred to comprises a series of squared notches 84 on the end of the spool sleeve 33^a defining shoulders which are adapted to be engaged by an arm 85 projecting laterally from a hand lever 86 projecting into the bifurcated end of a cap 87 which threads onto the end of the shaft 37. The lever is fulcrumed on a pin 88 extending through the cap. When the lever is positioned as shown in Fig. 5, the arm 85 is seated in one of the notches 84 thereby establishing a positive driving connection between the shaft and the spool. When the lever is swung into the position shown in dotted outline in Fig. 5, the

arm 85 is withdrawn from the notch and the spool is free to turn about the shaft yet restrained by the friction produced by the concave spring 42. The disengaged position of the clutch lever is maintained by a compression spring 89 acting between the nut 41 and a washer 90 enclosing the cap 87 and engaging an inclined surface 91 on the lever 86. When the clutch lever has been tipped out of disengaged position, the washer bears against a lug 92 and tends to swing the lever into engaged position whereupon the arm 85 will enter the next notch 84 which it encounters in the rotation of the shaft 37, the clutch being thereafter held engaged. In the engaged position of the clutch, the arm 85 does not project beyond the outer periphery of the sleeve 33^a thereby enabling the removable section 36 of the spool to be slid off from the sleeve 33^a and a new spool to be placed thereon.

It will be observed that by engaging one of the clutches and disengaging the other clutch of each pair of spools, the ribbon supported thereby will be conditioned for automatic advance of the ribbon through a predetermined distance each time the line-spacing lever 15 is actuated with the ribbon lowered into printing position. In such movement of the line-spacer, the slides 56 and 78 are shifted rearwardly which causes both ratchet units of the ribbon to be oscillated and the shafts 37 to be advanced a corresponding distance. The spool which is then coupled to its shaft is thus advanced, unwinding from the loose spool a corresponding length of ribbon and drawing the intermediate portion through its guides. Overrunning of the loose spool is effectually prevented by virtue of the friction due to the stress under which the associated spring 42 is maintained. At the limit of this movement, the check pawls of the ratchet mechanism on the clutched spool become effective to prevent any substantial amount of reverse movement thereby avoiding the development of any slack in the intermediate portion of the ribbon and consequent smudging of the printed copy. When the ribbon has been substantially wound off from the loose spool, the then engaged clutch is disengaged and the disengaged clutch is engaged whereupon the ribbon will be advanced in the reverse direction upon subsequent operation of the line spacer.

I claim as my invention:

1. In a typewriting machine having a laterally shiftable paper carriage carrying a rotary platen, the combination of a tube extending along the rear side of said carriage and pivotally mounted thereon, a pair of arms rigid with opposite ends of said tube and swingable forwardly and downwardly to a position overlying said platen, a pair of alined shafts rotatably mounted upon the forward ends of the respective arms, spools rotatably mounted on said shafts and each adapted to be coupled for rotation therewith or to be uncoupled therefrom, a copy-printing ribbon having opposite ends wound upon said spools and an intermediate portion stretched between said arms, a pair of oscillatory members on the free ends of said arms each having a ratchet drive connection with one of said shafts, a shaft extending through said tube and carrying cranks at opposite ends, a pair of horizontally reciprocable bars extending alongside of said arms and each having one end connected to the free end of one of said cranks and the other end connected to one of said members eccentrically of the axis thereof, and means operable as an inci-

dent to normal operation of said machine to reciprocate one of said bars.

2. In a typewriting machine having a laterally shiftable paper carriage, the combination of a pair of rigidly connected arms disposed at opposite ends of said carriage and pivotally mounted on said carriage for movement of their free ends toward and from the carriage, a pair of spools each rotatably mounted on the free 10 end of one of said arms, an auxiliary copy-printing ribbon having opposite ends wound onto said spools, a member mounted on said carriage at one end thereof and arranged for reciprocation automatically during operation of said machine, and means providing a disengageable one-way driving connection between said member and both of said spools including a part extending along and adapted for pivotal movement about the pivotal axis of said arms.

20 3. In a typewriting machine having a laterally shiftable paper carriage, the combination of an arm pivotally mounted on said carriage and swingable into a position substantially parallel to said carriage, a spool rotatably mounted on the free end of said arm, a copy-printing ribbon having one end wound on said spool, a bar mounted on said carriage for endwise reciprocation transversely of the axis of said arm, means for reciprocating said bar during operation of said machine, a crank pivotally mounted on the free end of said arm and having a disengageable one-way driving connection with said spool, and a flanged roller pivotally mounted on said crank and adapted to become seated in a 30 notch upon movement of said arm toward said bar.

4. In a typewriting machine having a carriage and a line spacer member thereon, the combination of an auxiliary printing ribbon, a 40 spool on which one end of said ribbon is wound, means supporting said spool for rotation and for bodily movement toward and away from said carriage, a ratchet wheel adapted to be coupled to said spool, a crank member pivotally mounted on said supporting means concentric with the axis of said wheel and carrying a pawl for advancing the wheel, a slide mounted on said carriage for endwise reciprocation parallel to said crank member during operation of said 45 line spacer member, and a lateral projection on the free end of said arm adapted to interengage with said slide and establish a driving connection between the slide and said crank member upon movement of said supporting means toward said carriage, said connection being interrupted upon movement of the supporting means away from the carriage.

5. In a typewriting machine having a laterally shiftable paper carriage, the combination of a support mounted on said carriage and movable toward and away from the latter, a spool rotatably mounted on said support, a copy-printing ribbon having one end wound on said spool, a bar mounted on said carriage for endwise reciprocation transversely of the direction of movement of said support, means for reciprocating said bar during operation of said machine, a crank pivotally mounted on said support and having a disengageable one-way driving connection with said spool, spring means normally tending to turn said crank relative to said support and acting when the crank is free to move the same to a predetermined limit position, and a lug and notch on said crank and said bar adapted to interengage in driving re-

lation upon movement of said arm toward said carriage with said crank in said limit position.

6. In a typewriting machine, the combination of a pair of auxiliary copy printing ribbons, a pair of spools each having one end of one of said ribbons wound thereon, a member supporting said spools side by side substantially in a common plane to turn about spaced parallel axes, a pair of crank arms pivotally mounted on said member and extending substantially parallel to each other but projecting in opposite directions, a one-way disengageable driving connection between each of said crank arms and one of said spools, and an actuating bar connected to the free ends of both of said cranks 10 and reciprocable back and forth periodically in the normal operation of said machine.

7. In a typewriting machine having a rotary platen, the combination of a support mounted on the machine for movement toward and away from said platen, a shaft rotatably mounted on and projecting from said support, means operable in the operation of said machine to advance said shaft step-by-step, a rotatable sleeve concentric with said shaft, a ribbon spool having a tubular hub fitting over and telescoping with said sleeve, a manually operable clutching element mounted on the end of said shaft and movable into and out of clutching engagement with the projecting end of said sleeve, the overall dimensions of said element being less than the diameter of said sleeve whereby to permit said spool to be removed from said sleeve.

8. In a typewriting machine having a horizontal paper carriage, the combination of a pair of vertically movable supports at opposite ends of said carriage, a pair of aligned shafts rotatably mounted on said supports and projecting toward each other, an auxiliary ribbon, a pair of spool sleeves each rotatably and removably mounted on one of said shafts and having the opposite ends of said ribbon wound thereon with the intermediate portion of the ribbon stretched between the sleeves, means operable during normal operation of said machine to advance one of said 30 shafts step-by-step, and a clutch at the end of each shaft operable to establish a driving connection between such shaft and the spool sleeve mounted thereon and having overall dimensions not greater than the hole in said spool sleeve 40 whereby to permit endwise removal of the spool sleeve over the clutch.

9. In a typewriting machine having a rotary platen, the combination of a support mounted on the machine for movement toward and away from said platen, a shaft rotatably mounted on and projecting from said support, means operable in the operation of said machine to advance said shaft step-by-step, a rotatable sleeve concentric with said shaft, and having annularly spaced shoulders at its projecting end, a ribbon spool removably mounted on said sleeve, and a bell crank lever pivoted on said shaft to swing about an axis extending transversely thereof and having an operating arm projecting from said 50 sleeve in an axial direction and a second arm movable into and out of engagement with said shoulders.

10. In a typewriting machine having a rotary platen, the combination of a support mounted on the machine for movement toward and away from said platen, a shaft rotatably mounted on and projecting from said support, means operable in the operation of said machine to advance said shaft step-by-step, a rotatable sleeve concentric

with said shaft, and having annularly spaced shoulders at its projecting end, a ribbon spool removably mounted on said sleeve, a bell-crank lever pivoted on said shaft to swing between two limit positions about an axis extending transversely of the shaft, said lever having an arm adapted, when in one of said positions, to engage

one of said shoulders, and spring means acting on said lever to permit the latter to remain in the other of said positions but operable, upon movement of the lever out of said last mentioned position, to urge the lever toward said first mentioned position.

LEWIS D. NELSON.
